UNITED STATES PATENT OFFICE.

CYRUS HILYAR, OF DEER PARK, WISCONSIN.

BUCK ANCHOR FOR FIREPROOF WALLS.

Application filed June 4, 1925. Serial No. 34,845.

This invention relates to anchoring devices for bucks for door frames or window frames interposed in walls constructed of a plurality of building units, such as fire proof tiles.

In constructing fire proof walls from tiles or other building units, it is desirable to have some efficient means interposed between layers of building units and cemented therebetween for securely anchoring the timber or portion of a door buck to maintain the same in proper upright position.

This invention has for its object to provide an exceedingly simple but highly efficient buck anchor which may be easily installed when the walls are being erected, having means for straddling a leg of a buck and securing the same in proper position to the adjacent edge of the wall.

It is a more specific object of the invention to provide such a buck anchor comprising a relatively flat elongated plate adapted to be set in the plaster or mortar between two layers of building units having means to prevent lateral longitudinal displacement thereof and having means projecting beyond an edge of the wall and adapted to engage the edges of a buck and be secured thereto.

It is a further object to provide a buck anchor provided at one end with a pair of flat projecting tongues adapted to be seated in oppositely aligned grooves in the edges of a 2x4 or other timber used for the door buck, said tongues being of sufficient length to extend beyond the outer surface of the buck, whereby the extremities of said tongues may be bent inwardly and nailed or otherwise secured to said outer surface.

It is a still further object of the invention to provide such a buck anchor especially adapted to engage and straddle a 2x4 but capable of being combined with another similar anchor to engage the leg of a buck constructed from larger timbers, such as 2x6's and 2x8's.

These and other objects of the invention will be apparent from the following description made in connection with the accompanying drawings, wherein like characters refer to similar parts throughout the several views, and in which,

Fig. 1 is a perspective view showing portions of a fire proof wall in the process of construction with a doorway formed therein and portions of a door buck mounted in said doorway, and a preferred form of the inven-

tion engaging said buck and securing the same to the walls in proper operative position.

Fig. 2 is a perspective view of a preferred form of the invention detached; and

Fig. 3 is a plan view of the end portions of a pair of buck anchors used in combination to accommodate a considerably wider buck than the 2x4 buck generally employed in buildings.

In the drawings, a wall, having an open portion therein constituting the doorway, is illustrated, said wall being constructed of a plurality of fire proof tiles or building units 4 laid in layers in the usual manner. The legs of a door buck are indicated by the numeral 5 having cut at intervals along the side edges thereof, the oppositely disposed aligned horizontal grooves 5^a. The grooves may be formed in the 2x4's or timbers constituting the door buck before the same are applied to the walls or, if desired, may be sawed, after the wall is partially up. The buck anchor comprises an elongated relatively flat member or plate designated as 6 an entirety by the letter "A", having a plurality of longitudinal corrugations 7 throughout its central portion and having a plurality of transverse corrugations 8 in the portion thereof adjacent one end. The corrugated plate A is provided at its outer end with a pair of flat, spaced, projecting tongues 9 forming a recess therebetween. Adjacent the outer extremities of tongues 9, small apertures are provided, the purpose of which will be presently explained. In manufacturing the buck anchors A, the blanks are cut out in dove-tailed relation, the tongues 9 being cut out from the opposite end of the adjacent blank, leaving the cut-away portions 10 at the rear end of each member A.

The grooves 5^a are cut in the edges of the 2x4's or other timbers used in the bucks at the level of the layers of building units constituting the walls. The plate A is laid longitudinally of the wall on the top surface of the layer of the tiles adjacent the edge of the wall defining one side of the doorway, and the body portion including the corrugations 6 and 7 when the buck anchor is embedded in the cement or mortar between two layers of the tile. The projecting tongues 9 are seated in the slots 5^a straddling the adjacent leg 5 of the

buck and securing the same against displacement. The tongues 8 are of sufficient length to project beyond the outer surface of the buck legs 5, forming small securing tabs which are bent either upwardly or downwardly and nailed or otherwise secured through apertures 8^a to the outer surface of the buck leg. As illustrated in Fig. 1, the buck anchors are interposed at intervals, 10 along vertical edges of the walls constituting the doorway, engaging the door buck and securely anchoring the same in proper operative position. Obviously, the corrugations 6 and 7, embedded in the mortar between two layers of the building tiles 4, prevent both lateral and longitudinal displacement of the plate A with respect to the wall. The tongues 8, seated in the grooves 5^a of the buck, engage said buck in edge-wise position, thereby affording straddling means of sufficient strength to hold the buck as desired.

As shown in Fig. 3, when a buck constructed of wider lumber is used, such as 25 2x6 or 2x8 boards, two of the plates A may be combined with the corresponding corrugations of each in registration. The inner tongues of each member A may then be bent over to engage the adjacent side of 30 the other member. The outer tongues 8 may then be employed to engage and straddle the wider buck used.

It will be seen from the above description that applicant has invented an exceedingly simple but highly efficient buck anchor comprising a single member and capable of being manufactured at little cost. Present devices for anchoring bucks rely for the most part on a bolt or other elongated member having a bent end adapted to engage one of the partitions in the tile. It may be readily seen that, if the bent end is not flush against its adjacent partition, the anchor will often slip longitudinally, thus permitting the buck to be displaced from the doorway. Applicant's device embedded in the cement or mortar absolutely prevents longitudinal or lateral displacement thereof and, moreover, straddles the buck having its straddling tongues secured at their extremities to the outer surface of the 2x4's or other lumber used.

Extensive actual usage of the device has shown the same to be highly efficient for all 55 the purposes intended.

It will, of course, be understood that various changes may be made in the form, details, proportions and arrangement of parts without departing from the scope of 60 the invention.

What is claimed is:—

1. A buck anchor comprising a substantially flat body adapted to be interposed between two layers of building units, a pair of spaced tongues at one end of said body 65 adapted to project beyond the ends of said building units to transversely straddle a buck and secure the same in proper working position, said tongues both lying in the same plane with said body. 70

2. A buck anchor comprising a relatively flat body adapted to be interposed between two layers of building units, one end of said body being centrally recessed to form a pair of spaced tongues both lying in the same 75 plane as said body and adapted to transversely straddle a buck to secure the same in proper working position.

3. The structure set forth in claim 2 and said tongues being of sufficient length to 80 project beyond the outer side of said buck and be bent at right angles and secured thereto.

4. The combination with a plurality of building units arranged in the form of a wall and a buck for a door frame or similar structure, said buck having oppositely disposed slots in the edges thereof; of a buck anchor comprising a relatively flat member adapted to be interposed between two layers 85 of said building units and having a pair of spaced tongues at one end thereof projecting beyond said wall and adapted to be seated in said slots of said buck to secure the same in proper working position. 90

5. The structure set forth in claim 3, and said tongues being of sufficient length to project beyond the outer side of said buck providing projecting portions adapted to be bent down against the outer surface of said 100 buck and secured thereto.

6. A buck anchor having in combination a plurality of units, each comprising a relatively flat body member having a pair of spaced projecting tongues at one end thereof of lying in substantially the same plane with said body member, the sides of said units being overlapped and the inner tongues being bent around the end of the body member adjacent thereto, means for preventing 105 said units from lateral displacement from each other, said units in overlapped position being adapted to be interposed between two layers of building units with the outer tongues of the outer units projecting beyond the ends of said building units adapted to straddle and anchor a buck. 110

In testimony whereof I affix my signature.

CYRUS HILYAR.
